CLAIM

The ornamental design for a fireplace match holder, substantially as shown and described.

DESCRIPTION

FIG. 1 is a top plan view of the quiver;

FIG. 2 is a bottom plan view;

FIG. 3 is a front end elevational view of the quiver;

FIG. 4 is a rear end elevational view of the quiver; and FIG. 5 is an elevational view of one side of the quiver, the opposite side of which appears the same.
